UNITED STATES PATENT OFFICE.

BURT R. VAN VALKENBURG, OF OAKLAND, CALIFORNIA.

PIANO-PLAYING MECHANISM.

1,074,563.

Specification of Letters Patent. Patented Sept. 30, 1913.

Application filed January 3, 1912. Serial No. 669,240.

To all whom it may concern:

Be it known that I, BURT R. VAN VALKENBURG, a citizen of the United States, residing at Oakland, in the county of Alameda and State of California, have invented 5 certain new and useful Improvements in Piano-Playing Mechanism, of which the following is a specification.

This invention relates to player pianos of 10 the type wherein a roll of perforated paper is used to control the production of musical notes.

The principal object of the invention is to provide a player piano having a duplicate 15 set of roll actuating mechanisms so that one roll may be used during the rewinding and changing of a second roll, thus making the piano a substantially continuous player.

A second object of the invention is to provide 20 a piano of the class described wherein but a single set of pneumatics and hammer mechanisms will be necessary, the pneumatics being controlled at will from either of the rolls.

A third object of the invention is to provide 25 separate mechanisms for controlling the speed of operation by either of the winding devices at will.

A fourth object of the invention is to provide 30 separate braking means for the winding rolls of the two mechanisms, said braking means being automatically arranged to switch from one to the other of the roll winding mechanisms in inverse order of actuation. That is to say, when one of the roll winding mechanisms is in use the other mechanism will be acted upon by the braking device.

With the above and other objects in view, 35 the invention consists in general of certain novel details of construction, combinations and arrangements of parts, as will be hereinafter fully described, illustrated in the accompanying drawings, and specifically 40 claimed.

In the accompanying drawings, like characters of reference indicate like parts in the several views, and: Figure 1 is a front elevation partly in section of a player piano 45 showing the mechanism forming the invention installed therein. Fig. 2 is a transverse section through such a piano. Fig. 3 is a plan view of a portion of the device on the line 3—3, Fig. 2. Fig. 4 is a plan view of a certain valve arrangement used in connection herewith. Fig. 5 is a section on the line

5—5, Fig. 4. Fig. 6 is a section through a certain tempo control box. Fig. 7 is a section on the line 7—7, Fig. 6. Fig. 8 is a section on the line 8—8, Fig. 1. Fig. 9 is 60 a horizontal section showing a certain lever arrangement, the section being taken below the keys of a piano. Fig. 10 is a section showing a finger control valve. Fig. 11 is a detail section showing a certain clutch 65 used herewith.

The piano constructed in accordance with this invention is provided with the usual casing 10 wherein is mounted the piano action indicated in general at 11 and this action may be controlled manually from keys 12 or may be operated by means of bellows 13 arranged in the usual manner along the vacuum trunk 14 in which vacuum is maintained by means of a vacuum bellows or 75 pump, not shown.

Turning now to the device which forms the special and essential part of this invention there is disclosed in the front of the instrument a double casing 15 which is separated by a partition 16 into upper and lower compartments 17 and 18, respectively. In each of the compartments 17 and 18 there is provided a roll receiving mechanism arranged to receive the journals 19 of the usual 80 music roll 20. Included in each of the roll receiving mechanisms is a shaft 21 having at one end a clutch which engages the clutch end of the music roll 20, and at the other end of the shaft there is provided a sprocket 90 22. Below each of the music rolls 20 there is provided a winding roll journaled in suitable bearings and having a flange 23 at each end. On one of the journals 23 of the winding roll there is a gear 24 which meshes 95 with a pinion 25 carried on a short shaft 26 whereon are spaced pins 27 which have mounted between them a ring 29 which is engaged by the yoke end of a shipper lever 28.

Two separate operating engines are provided indicated at 30, and each of these engines has the usual crank shaft 31 whereon is fixed a sprocket 32 which is connected by means of a chain 33 to a sprocket 34 on a 105 shaft carrying a sprocket 35 which is connected by means of a chain 36 with the sprocket 32.

When the shipper lever 28 is moved in one direction the winding roll will be caused to 110 operate while if the shipper lever be moved in the opposite direction the pinion 25 will

disengage from the gear 24 and the roll will rewind, and thus by proper manipulation of one or the other of the shipper levers 28 the rolls may be caused to play at will.

5 Leading to the chambers 17 and 18 is a tracker bar 37 of the usual construction. On the back of the casing 16 there are provided brackets 38 whereon is mounted a valved board 39 having a series of holes extending vertically therethrough as at 40 and a series of holes of like character at 41, the series being in alternate relation to each other and in order to economize in length the holes are arranged in diagonal lines as 15 can readily be seen by reference to Fig. 3. Secured in each of the holes 40 and 41 is an upwardly extending tube 42. Beneath this board and resting directly on the brackets is a similar board 43 having a single series of 20 holes 44 arranged in diagonal lines but spaced at a distance equal to twice the distance between a hole 40 and the next adjacent hole 41 so that as the upper board is moved longitudinally of the lower board one 25 or the other of the series 40 or 41 is brought into registry with the series 44. Extending downward from each of the holes 44 is a short tube 45. In the board 39 there is provided a pair of slots 46 wherethrough extend screws 47 provided with washers 48 so that the two boards 39 and 43 are securely held together and the entry of air between the two prevented. From the upper tracker board 37 a series of tubes 49 extend to one of 30 the series 40 or 41, being connected by means of the short tubes 42 while from the lower tracker board a similar series of tubes 50 are connected in like manner with the remaining series 40 or 41 as the case may be. On the 35 end of the casing 15 there is provided a bracket 51 whereon is pivoted a lever 52 which is connected by means of a link 53 with the board 39 so that as this lever is moved in one direction or the other in like 40 manner will the board 39 be moved to one side or the other and bring one of the series 40 or 41 of holes into communication with the series of holes 44.

In order to provide means to brake the 50 winding roll when the record is being rewound the casing is provided with brackets 54 whereto are pivoted levers 54 which are connected at one end to a plunger 55 carrying a brake shoe 60 which is held against the flange of the winding roll, by means of a spring 60'. The other end of each of the levers 54 lies beneath the movable board 61 and pneumatics 62. Leading from the pneumatics 62 are tubes 63 and 64, the tubes 55 leading in the order named from the upper and lower pneumatics. The tube 63 is connected to an opening 65 in the board 39 while the tube 64 is connected to a similar opening 66. In the board 43 are openings 67 and 68 which register respectively with

the openings 65 and 66 accordingly as the board 39 is moved toward one end or the other of the board 43. For instance if the boards are in the position shown in Fig. 3 the openings 66 and 68 will be in registry 70 and in consequence the upper pneumatic 62 will be deflated since the openings 67 and 68 are connected by suitable tubing to the vacuum trunk 14. As this pneumatic is deflated the brake shoe 60 will be raised off of 75 the flange 23, and the winding roll permitted to operate without interference. It is to be noted that the lower board 43 is provided with suitable bleeder openings 66' properly positioned with which the openings 65 and 80 66 are in registry when the upper board is moved to the respective end.

Leading from the engines 30 are pipes 69 and 70 the pipes leading from the lower and upper engines respectively. The pipes 69 and 70 lead to tempo control boxes 71 and 72. Each of these boxes is provided with spaced ports 73 and 74. Adjacent each of the openings 73 and 74 are spaced guides 75 and over the opening 73 extends a plate 90 76 having a slot 77 therein, said slot being rounded at one end and terminating in an acute angle at the opposite end so that as the plate is moved over the port 73 the amount of opening may be varied at will 95 and adjusted, thus regulating the tempo of the music by controlling the speed of the engines, this being accomplished by the greater or less degree of vacuum in the respective pipe 69 or 70. This valve plate 76 has 100 a stem 78 extending therefrom and the box 72 has its stem connected to a lever 79 which terminates in a thumb piece 80 extending upward adjacent the key slip 81 of the piano. The valve stem 78 which projects 105 from the other control box is in like manner connected to a lever 82 and this lever has connected to its upper end a link 83 terminating in a finger piece 84 adjacent the thumb piece 80. 110

Leading from the ports 73 are vacuum pipes 85 which unite and are connected with an equalizing bellows 86. The ports 74 are controlled by means of valves 87 moving in the remaining guides 75 and provided 115 with an opening 88 corresponding to the port 74. These slide valves 87 are also provided with stems 89 which are connected to the moving members of pneumatic bellows 90, the latter in turn being connected by 120 tubes 91 which lead to a chest 92 from whence lead tubes 93 which terminate in controlling valves 94 having push buttons 95 whereby the valve may be opened to the atmosphere. Leading from the ports 74 125 are tubes 96 which communicate with the main bellows, not shown. Connecting the chest 92 with the tube 96 is a short tube 97.

It will be noted that by having the V-shaped side of the valve next to the equaliz- 130

ing bellows and the valve with the round opening communicating with the main bellows rewinding can be accomplished at a higher rate of speed than the unwinding.

5 In the chest 92 there are provided suitable pneumatics illustrated in Fig. 8 for controlling the deflation of the respective bellows 90.

10 There has thus been provided a simple and efficient device of the kind described and for the purpose specified.

15 It is obvious that many minor changes may be made in the form and construction thereof without departing from the material principles thereof and it is not wished to confine the invention to the exact form herein shown and described but it is wished to include all such as properly come within the scope of the appended claims.

20 Having thus described the invention, what is claimed as new, is:—

1. In a player piano, a plurality of motors, an equal number of control boxes, conductors leading from said motors to said 25 control boxes; a conductor leading from the main bellows of said player piano and communicating with said control boxes, valves for controlling the entrance from said control boxes to said last mentioned conductor, 30 a bellows for operating each of said valves, a vacuum chest, tubes leading from said bellows to said chest, a tube leading from said vacuum chest to said last mentioned con-

ductor, controlling levers for said tubes leading from said bellows, an equalizing bellows, 35 pipes leading from said control boxes and communicating with said equalizing bellows, and manually controlled valves for opening and closing the passageway between said control boxes and said last mentioned pipes. 40

2. In a player piano, a plurality of motors, an equal number of control boxes, a pipe leading from each motor to its respective control box, an equalizing bellows, pipes leading from said control boxes to said 45 equalizing bellows, manually controlled valves for opening and closing the entrance from said control boxes to said last mentioned pipes, a pipe leading from the main bellows of said player piano and communicating with said control boxes, valves for opening and closing the entrance from said control boxes to said last mentioned pipe, bellows for operating said last mentioned valves, a vacuum chest, a pipe leading from 50 said vacuum chest to said last mentioned pipe, tubes leading from said last mentioned bellows to said vacuum chest, and manually controlled means for opening and closing the entrance from said chest to said tubes. 55

60 In testimony whereof I affix my signature in presence of two witnesses.
